CLAIM

The ornamental design for a dispensing closure, as shown and described.

DESCRIPTION

FIG. 1 is a front perspective view of a dispensing closure showing our new design;

FIG. 2 is a top plan view thereof;

FIG. 3 is a front elevational view thereof;

FIG. 4 is a left-side elevational view thereof, the right-side being a mirror image;

FIG. 5 is a rear elevational view thereof; and,

FIG. 6 is a top front perspective view thereof, the spout in an open position. The bottom of the dispensing closure is unornamented.
